(57) CLAIM

The ornamental design for clothing having detachable portions, as shown and described.

DESCRIPTION

FIG. 1 is a front view of the clothing having detachable portions showing my new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines showing the body of the user and seams are for illustrative purposes only and form no part of the claimed design.
